[57] ABSTRACT

A two-pole electronic starter for use with a fluorescent lamp of the type having filament-like electrodes,

for preheating the filament-like electrodes of the fluorescent lamp and thereafter for starting said lamp, said starter comprising a pair of terminals adapted to be electrically connected each to a respective one of the filaments of said fluorescent lamp in order to form with said filaments a series circuit adapted to be electrically connected in turn to a source of alternating current voltage, a bidirectional-conduction electronic switch having a control input and connected between said pair of terminals, and a threshold trigger circuit for delivering control pulses to said control input of said bidirectional-conduction electronic switch, said threshold trigger circuit comprising a threshold diode having one electrode connected to said control input of said electronic switch, a capacitor having one plate connected to the other electrode of said threshold diode, and a voltage divider connected in series across said pair of terminals and provided with an intermediate tap connected to the junction point between said threshold diode and said capacitor, said voltage divider comprising means for shifting the potential of said tap in such a direction that at each half-wave of the supply a.c. voltage, after a predetermined time period for which the voltage applied to the fluorescent lamp is normally sufficient for starting same, becomes lower than the threshold level of said threshold diode in order to keep said electronic switch in a non-conducting state.

TWO-POLE ELECTRONIC STARTER FOR FLUORESCENT LAMPS

BACKGROUND OF THE INVENTION.

The present invention relates to a two-pole electronic starter for use with a fluorescent lamp of the type having filament-like electrodes, for preheating the filament-like electrodes of the fluorescent lamp and thereafter for starting said lamp, said starter comprising a pair of terminals, each adapted to be electrically connected to a respective one of the filaments of the fluorescent lamp in order to constitute with said filaments a series circuit adapted to be connected in turn to a source of alternating current.

To ensure the ignition of a fluorescent lamp under satisfactory conditions, that is, with the maximum efficiency and without damaging the lamp filaments or reducing its useful life, it is necessary to preheat the filaments and then applying thereto during a very short time, a voltage sufficient for striking an arc between the lamp electrodes.

SUMMARY OF THE INVENTION

It is the essential object of the present invention to provide a two-pole electronic starter of the above defined type, capable of performing the above- disclosed function while permitting a quick ignition or start of the fluorescent lamp with which it is associated, irrespective of the lamp type concerned and without resorting to preheating windings in the supply ballast which is usually connected in series with the fluorescent lamp.

To this end, the two-pole electronic starter according to this invention is characterized in that it comprises, between its two terminals, a bidirectional conduction electronic switch and a threshold trigger circuit for delivering control pulses to a control input of the bidirectional-conduction electronic switch, the threshold trigger circuit comprising essentially a threshold diode having one electrode connected to said electronic switch control input and an other electrode connected to one plate of a capacitor which plate is connected in turn to an intermediate tap of a voltage divider which is connected between the two terminals of said starter and constitutes a charging circuit and a discharge circuit for said capacitor, and in that said voltage divider comprises means for shifting the potential of said intermediate tap in such a direction that the voltage wherat said capacitor is charged at each half-wave of the a.c. supply voltage, after a predetermined time period for which the voltage applied to the fluorescent lamp is normally sufficient for starting same, becomes lower than the threshold level of the threshold diode, in order to keep said electronic switch in a non-conducting state.

With this arrangement, when an ON-OFF switch inserted in the supply circuit of the fluorescent lamp is closed, the bidirectional conduction electronic switch, which may advantageously consist of a triac, is firstly controlled in a manner to cause said switch to assume its conducting state during at least a certain time period upon each half-wave of the a.c. supply voltage, in order to permit the passage of heating current through the filaments of the fluorescent lamp, this condition being maintained during a predetermined time period after the closing of said ON-OFF switch, whereafter the elec-

trodes of the fluorescent lamp are heated sufficiently to cause the starting thereof. At the end of this predetermined time period, the triac stops conducting and two possibilities arise: either the fluorescent lamp is started and the arc struck between its electrodes shunts the starter so that the latter remains inoperative, or the fluorescent lamp is not started and another preheating cycle begins for restoring the lamp starting conditions, until the fluorescent lamp is actually lighted.

BRIEF DESCRIPTION OF THE DRAWINGS.

A detailed description of various forms of embodiment of the present invention will now be given by way of example with reference to the attached drawings, in

15

FIG. 1 is a wiring diagram of a fluorescent lamp equipped with a two-pole electronic starter according to a first embodiment of the present invention;

20 FIG. 2 is a diagram showing the pattern of the voltage oscillations across the terminals of the fluorescent lamp during an attempt of starting the lamp;

25 FIGS. 3 to 5 are other wiring diagrams illustrating modifications of the embodiment of the two-pole electronic starter illustrated in FIG. 1;

30 FIG. 6 is a wiring diagram of a fluorescent lamp equipped with a two-pole electronic starter according to another embodiment of this invention; and

35 FIG. 7 is a wiring diagram illustrating a modification of the embodiment of the electronic starter of FIG. 6, for starting two fluorescent lamps disposed in series.

DESCRIPTION OF THE PREFERRED EMBODIMENTS.

The two-pole electronic starter 1 illustrated in FIG. 35 1, intended for starting a fluorescent lamp L, comprises a pair of terminals 1a and 1b connected to the filament-like electrodes 2 and 3 of the fluorescent lamp L, respectively, so as to constitute with these filaments a series circuit adapted in turn to be connected to a source of alternating current (not shown), via a stabilizing choke or ballast S and an usual ON-OFF switch (not shown).

40 According to this invention, the two-pole electronic starter 1 comprises across its terminals 1a and 1b a bidirectional electronic switch advantageously consisting of a triac 4, and a threshold-type trigger circuit for delivering a control pulse to the gate electrode 4a of said triac 4. This threshold type trigger circuit comprises essentially a threshold diode such as a diac 5 having one electrode connected to the gate electrode 4a of said triac and its other electrode connected to one of the plates of a capacitor C₂ having its other plate connected to the common electrode of said triac. The first-mentioned plate of capacitor C₂ is connected to a tap 6 of a voltage divider which is fed from the a.c. source and constitutes a charging circuit and a discharge circuit for capacitor C₂. In the embodiment illustrated in FIG. 1 this voltage divider comprises on the one hand a pair of resistors R₁ and R₂ mounted in series between the terminal 1a of the starter and tap 6, to constitute the charging circuit of capacitor C₂, and on the other hand another pair of resistors R₃ and R₄ constituting a parallel circuit mounted in turn in parallel to capacitor C₂.

60 65 According to a specific feature characterizing this invention, the voltage divider comprises means for causing the potential of said tap 6 to shift in such direction

that the voltage whereat said capacitor C_2 is charged at each half-wave of the a.c. supply voltage after a predetermined time period for which the voltage fed to the fluorescent lamp L is normally sufficient to start same, becomes lower than the threshold level of diac 5. This means may consist for example of resistor R_3 which can be a resistor of the type having a negative temperature coefficient, disposed in proper heat-transfer relationship with a heating resistor R_5 connected in series with triac 4 across the starter terminals 1a and 1b.

A capacitor C_1 having a function to be explained presently is connected in parallel to said triac 4. More particularly, one of the plates of this capacitor C_1 is connected to the common electrode of triac 4, and its other plate is connected to the junction point of resistors R_1 and R_2 , so that in fact it is the series circuit comprising the resistor R_1 and capacitor C_1 that is connected in parallel to said triac 4.

The above-described electronic starter operates as follows. When at a given time t_0 (FIG. 2) the main switch provided in the supply circuit of lamp L is closed, the threshold trigger circuit of triac 4 is energized. When for each half-wave of the a.c. supply voltage the voltage across the terminals of capacitor C_2 becomes higher than the threshold level of diac 5, the latter delivers to the gate electrode 4a of triac 4 a trigger pulse causing this triac to assume its conducting state. Thus, heating current flows through the filaments 2 and 3 of fluorescent lamp L . This heating current also flows through resistor R_5 provided for heating resistor R_3 having a negative temperature coefficient. Consequently, the resistance value of resistor R_3 decreases and may thus drop to a value such that the voltage across the terminals of capacitor C_2 becomes lower than the threshold level of diac 5, whereby the triac 4 becomes non-conducting. This change in the mode of operation of the circuit leads to the production of an oscillatory overvoltage in the oscillating circuit comprising the stabilizing choke S and capacitor C_1 . As a result, a pulse is generated and applied to the electrodes of the fluorescent lamp L . By properly calculating the different values of the circuit component elements, it is possible to cause said change (in the mode of operation) to take place at a predetermined time t_1 after the moment t_0 (FIG. 2), the time period t_1-t_0 being both long enough to allow the filaments 2 and 3 of lamp L to be properly heated and short enough to produce a rapid starting or ignition of said lamp, and to cause the cut-off overvoltage produced at said time t_1 and applied across the terminals of lamp L to be of a sufficient magnitude to start this lamp. The function of resistor R_4 is to prevent the starter from resuming its operation once the lamp L has been lighted. More particularly, the value of said resistor R_4 is so selected that after the starting of lamp L , as the electric arc struck across the lamp electrodes is substantially shunting or by-passing the electronic starter 1, the voltage then appearing across the ends of said resistor R_4 and applied to capacitor C_2 remains under all circumstances lower than the threshold voltage of diac 5. The function of resistor R_1 is to reduce the time necessary for the current flowing through the triac to build up.

FIG. 2 illustrates the evolution of the operation of the electronic starter 1 during a complete attempt to start a fluorescent lamp L . In this Figure, A designates the waveform of the a.c. supply voltage, B is the waveform of the voltage across the triac terminals during the time

period corresponding to the heating of filaments 2 and 3, and C is the waveform of the arc voltage of the lamp after the latter has been started at time t_1 . As shown in FIG. 2, when the main switch (not shown) inserted in the supply circuit of lamp L is closed, the triac is rendered conducting by the mains voltage fed to the threshold trigger circuit via the stabilizing choke S and the filaments 2 and 3 of lamp L . At the triac cut-off during the first halfwave of the a.c. supply voltage, 10 when the momentary value of the heating current is zero, the a.c. supply voltage being substantially at its peak value, the series oscillating circuit comprising said stabilizing choke S and capacitor C_1 begins to oscillate freely. The above-described threshold trigger circuit is 15 so designed that at each half-wave the triac is rendered conducting by the oscillating overvoltage, not by the sine wave of the a.c. supply voltage. The natural frequency of the oscillating condition must then be low enough to prevent the impedance of capacitor C_2 from 20 becoming abnormally low at said frequency. As the negative temperature coefficient resistor R_3 is heated by resistor R_5 , its ohmic value decreases at each half-wave of the a.c. supply voltage.

As a consequence of this reduction in the ohmic 25 value of resistor R_3 , the momentary value of the oscillating voltage to be fed to the trigger circuit of the triac for bringing this triac to the conducting state increases at each half-wave until, for a certain half-wave, it reaches a value approximating the peak value of this 30 oscillating voltage before the triac is turned-off. During this last half-wave, the transitory voltage resulting from the triac cut-off at time t_1 will be the pulse having the greatest amplitude during a cycle of operation of the 35 starter, and the pulse is applied across the terminals of the fluorescent lamp for starting it.

If at the end of this first cycle of operation the fluorescent lamp is not started or lighted, the starter is stopped to permit the cooling of resistor R_3 , and then 40 the same cycle is repeated as many times as required for starting the lamp. Thus, at each attempt to start the lamp, the lamp filaments are pre-heated and this pre-heating is obtained by virtue of the triac inserted in series with the lamp filaments and so controlled as to be 45 recurrently conducting during a predetermined time period.

In case the fluorescent lamp were de-activated, the 50 starter would operate as in the preceding case, that is, in a relaxation mode. Thus, the average current flowing through the stabilizing choke S and through the triac 4 will be very low and any risk of abnormally heating this choke of said triac will safely be precluded.

The above-described electronic starter is of completely static and thermo-controlled character. Therefore, no mechanical adjustment is required during its manufacture, and the risk of damaging movable contacts is definitely precluded since the device is free of any contact whatsoever. This feature is particularly advantageous in comparison with conventional starters incorporating a bimetallic strip. The electronic starter according to the present invention is attended by many other advantageous features, inter alia:

1. by acting on the heating resistor R_5 , i.e., on its ohmic value or its position in relation to the negative-temperature coefficient resistor R_3 , it is possible to adjust the heating time and therefore the time required for starting the fluorescent lamp. 2. in case the fluorescent lamp failed to light up, notably if one of its fila-

ments were broken, the starter operation will be stopped immediately. 3. the fluorescent lamp cannot be lighted if its filaments have not been pre-heated sufficiently (and provided however that the heating time has been properly determined), thus ensuring an improved behaviour of the fluorescent lamps equipped with an electronic starter according to this invention, from the point of view of repeated ignitions, which are of the order of 100,000 ignitions (instead of about 40,000 in the case of a conventional glow-type starter). 4. the electronic starter according to this invention can be used with a capacitive stabilizing circuit for fluorescent lamp. The starting time and the number of ignitions of the lamp are therefore independent of the specific nature of the stabilizing circuit. 5. the same starter circuit diagram may be used for fluorescent lamps of different power ratings supplied with different voltages. Thus, for the various current ranges it is only necessary to change the ohmic value of the heating resistance R_5 , and for the different voltage ranges it is only necessary to modify the ohmic value of resistor R_2 .

By way of non-limiting exemplary illustration and considering the starting of a 215-Watt fluorescent lamp supplied from a 380-Volt mains, an electronic starter of the type illustrated in FIG. 1 was used; the component elements of this starter had the following values, respectively:

Triac	4.5 Amp., 800 V
Capacitor C_1	33 nF, 1,000 V
Capacitor C_2	22 nF, 250 V
Resistor R_1	100 Ohms, 1 Watt
Resistor R_2	100 kilohms, 1 Watt
Resistor R_3	N T C 150 kilohms
Resistor R_4	24 kilohms, 0.5 Watt
Resistor R_5	0.8 ohm.

FIGS. 3 to 5 inclusive illustrate modified embodiments of the electronic starter according to this invention.

The modified embodiment illustrated in FIG. 3 differs from the circuit of FIG. 1 in that resistor R_2 is eliminated and the voltage divider comprises in this case on the one hand a resistor R_1 and a capacitor C_1 mounted in series across terminal $1a$ and tap 6 , and on the other hand the negative temperature coefficient resistor R_3 and heating resistor R_5 mounted in series, this series mounting being connected in turn in parallel to capacitor C_2 . This capacitor C_2 has its plate opposite to that connected to the tap 6 connected to terminal $1b$, and the junction point between resistor R_3 and resistor R_5 is connected to the common electrode of triac 4 . In this modified embodiment, due to the moderate resistance value of resistor R_5 , it is admitted that resistor R_3 is also in this case mounted in parallel to capacitor C_2 in order to determine the voltage applied thereto and therefore the voltage applied to diac 5 .

The modified embodiment illustrated in FIG. 4 differs from that shown in FIG. 1 in that the voltage divider consists in this case on the one hand of resistor R_1 , capacitor C_1 and resistor R_2 mounted in series between terminal $1a$ and tap 6 , and on the other hand, of the negative temperature coefficient resistor R_3 connected in parallel to capacitor C_2 having its plate opposite to that connected to said tap 6 connected to terminal $1b$. A capacitor C_3 is connected in parallel to the series circuit comprising resistor R_2 and capacitor C_2 . Also in this case the negative temperature coefficient

resistor R_3 permits of determining the voltage across the terminals of capacitor C_2 .

The modified embodiment of FIG. 5 differs from that shown in FIG. 3 in that the negative temperature coefficient resistor R_3 is connected directly in parallel to capacitor C_2 , without passing through the heating resistor R_5 , and that a capacitor C_4 is connected in parallel to the series circuit comprising the pair of capacitors C_1 and C_2 . Also in this case the negative temperature coefficient resistor R_3 permits of determining the voltage across the terminals of capacitor C_2 .

The operation of the electronic starters according to the various embodiments illustrated in FIG. 3 to 5 is substantially the same as that of the starter shown in FIG. 1. In all cases, the negative temperature coefficient resistor R_3 permits of shifting the potential of the tap 6 in such direction that after a predetermined time period following the closing of a switch inserted in the supply circuit or mains circuit of the lamp, the voltage across the terminals of capacitor C_2 becomes lower than the threshold voltage of diac 5 in order to maintain the triac 4 in the non-conducting state.

Although the form of embodiment of the electronic starter described with reference to FIG. 1 and its various modifications described with reference to FIG. 3 to 5 are applicable to the starting of high-power fluorescent lamps, supplied from the 380-Volt mains, the triac used for this purpose must be particularly powerful and capable of withstanding a relatively high maximum peak voltage. Such triacs are relatively expensive and in this case a preferred solution may consist in utilizing an electronic starter comprising, according to a second embodiment of this invention, a second bidirectional-conduction electronic switch mounted in series with the first bidirectional-conduction electronic switch, and a second threshold-type trigger circuit for this second electronic switch, the capacitor of the first threshold-type trigger circuit and the means provided for shifting the potential (i.e., the voltage across the terminals of this capacitor) being common to both threshold-type trigger circuits.

This second embodiment will now be described with reference to FIG. 6 and 7 of the drawings in which the same reference numerals as in FIG. 1 are used for designating similar elements, or elements having the same function as in the first embodiment illustrated in FIG. 1. As in the first embodiment, the two-pole electronic starter illustrated in FIG. 6 comprises a bidirectional-conduction electronic switch consisting, for example, of a triac $4A$, and a threshold-type trigger circuit for delivering a control or trigger pulse to the gate electrode of said triac $4A$. This threshold trigger circuit comprises essentially a threshold diode such as a diac $5A$, having one electrode connected to the gate electrode of triac $4A$ and its other electrode connected to one of the plates of a capacitor C_2 . This plate of capacitor C_2 is also connected to a tap $6A$ of a voltage divider comprising means for shifting the potential of said tap point $6A$ in a direction such that the voltage at which the capacitor C_2 is charged at each half-wave of the a.c. supply voltage, after a predetermined time period for which the voltage applied to the fluorescent lamp L is normally sufficient to start same, becomes lower to the threshold voltage of diac $5A$. This means may consist for example of a resistor R_3 of the negative temperature coefficient type, connected in parallel to said capacitor C_2 and disposed in heat-transfer relationship with a

heating resistor R_5 connected in series to said triac 4A.

The two-pole electronic starter illustrated in FIG. 6 further comprises a second bidirectional-conduction electronic switch consisting for example of a second triac 4B, and a second threshold trigger circuit identical with the first threshold trigger circuit, for delivering control pulses to the gate electrode of the second triac 4B; moreover the capacitor C_2 , the negative temperature coefficient resistor R_3 and the heating resistor R_5 are common to both threshold trigger circuits. The threshold diode, such as a diac 5B, of the second threshold trigger circuit, is connected between the gate electrode of triac 4B and the other plate of capacitor C_2 .

Both triacs 4A and 4B are mounted in opposition with the heating resistor R_5 interconnected therebetween, the pair of triacs and the heating resistor constituting a series circuit connected across the starter terminals 1a and 1b. The negative temperature coefficient resistor R_3 is connected in parallel to another resistor R_7 , the parallel circuit thus obtained being connected in turn, in series, with a pair of resistors R_{6A} and R_{6B} , between these two resistors, the resulting series circuit unit being connected in turn in parallel to capacitor C_2 . The values of resistors R_3 , R_{6A} , R_{6B} and R_7 are selected to cause the equivalent resistance of the above-mentioned series circuit to have such a value that, when the fluorescent lamp L has been lighted the voltage whereat the capacitor C_2 is charged at each half-wave of the a.c. supply voltage remains lower than the threshold voltage of diacs 5A and 5B in order to keep both triacs 4A and 4B in the non-conducting state.

The voltage dividers included in the two threshold trigger circuits are completed by a resistor R_{2A} connected between junction point 6A and terminal 1a, and by a resistor R_2 connected between junction point 6B and terminal 1b. Moreover, a capacitor C_1 and a resistor R_2 are connected in series between the starter terminals 1a and 1b.

The mode of operation of the electronic starter illustrated in FIG. 6 is substantially the same as that of the one shown in FIG. 1; therefore, a detailed description of this mode of operation is not deemed necessary.

FIG. 7 shows a modified embodiment of the arrangement shown in FIG. 6. In this modified embodiment the heating resistor R_5 is not connected directly to the common electrode of triac 4A but to an auxiliary terminal 7, and the common electrode of triac 4A is connected to another auxiliary terminal 8. Both auxiliary terminals 7 and 8 may be selectively interconnected either through a removable short-circuit member such as a connecting strip 9 (in this case the resultant circuit diagram is equivalent to the circuit diagram illustrated in FIG. 6), or through the series-connected relevant filaments 3 and 2 of a pair of fluorescent lamps L_1 and L_2 connected in series across the two main terminals 1a and 1b of the starter. Thus, by bringing but a very simple modification of the circuit illustrated in FIG. 6, i.e., by adding the two auxiliary terminals 7 and 8, and the removable short-circuit member 9, it is possible to obtain an electronic starter adapted to be operated either for lighting a single fluorescent lamp connected across terminals 1a and 1b, in which case the short-circuit member 9 is connected or plugged in across the auxiliary terminals 7 and 8, or for starting a pair of fluorescent lamps L_1 and L_2 mounted in series, the short-

circuit member 9 being removed and the filaments 2, 3 of lamp L_1 being connected to terminal 1a and auxiliary terminal 8, respectively, whereas the filaments 2 and 3 of fluorescent lamp L_2 are connected to the auxiliary terminal 7 and terminal 1b, respectively, and filament 3 of lamp L_1 and filament 2 of lamp L_2 being connected in series.

Of course, the various embodiments described hereinabove are given by way of illustration only and should not be construed as limiting the field of the present invention, since many modifications may be brought thereto without departing from the basic principles of the invention as set forth in the appended claims. Thus, notably, other means may be used for shifting the potential of tap point 6 in the manner mentioned hereinabove. For instance, instead of the negative temperature coefficient resistor r_3 , a resistor having a fixed ohmic value may be used, and in lieu of the fixed ohmic value resistor R_2 of FIG. 1, a positive temperature coefficient resistor arranged in heat transfer relationship to the heating resistor R_5 may be contemplated.

What we claim is:

1. A two-pole electronic starter for use with a fluorescent lamp of the type having filament-like electrodes, for preheating the filament-like electrodes of the fluorescent lamp and thereafter for starting said lamp, said starter comprising a pair of terminals adapted to be electrically connected each to a respective one of the filaments of said fluorescent lamp in order to form with said filaments of said fluorescent lamp in order to form with said filaments a series circuit adapted to be electrically connected in turn to a source of alternating current voltage, a bidirectional-conduction electronic switch having a control input and connected between said pair of terminals, and a threshold trigger circuit for delivering control pulses to said control input of said bidirectional-conduction electronic switch, said threshold trigger circuit comprising a threshold diode having one electrode connected to said control input of said electronic switch, a capacitor having one plate connected to the other electrode of said threshold diode, and a voltage divider connected in series across said pair of terminals and provided with an intermediate tap connected to the junction point between said threshold diode and said capacitor, said voltage divider comprising means for shifting the potential of said tap in such a direction that at each half-wave of the supply a.c. voltage, after a predetermined time period for which the voltage applied to the fluorescent lamp is normally sufficient for starting same, becomes lower than the threshold level of said threshold diode in order to keep said electronic switch in a non-conducting state.
2. Electronic starter as set forth in claim 1, wherein said means consists of a negative temperature coefficient resistor connected in parallel to said capacitor and arranged in heat transfer relationship with a heating resistor connected in turn in series to said electronic switch.
3. Electronic starter as set forth in claim 2, wherein said negative temperature coefficient resistor and the heating resistor associated therewith are connected in series, the series circuit thus obtained being connected in turn in parallel to said capacitor, a junction point between said negative temperature coefficient resistor and said heating resistor being connected to said electronic switch.

4. Electronic starter as set forth in claim 1, wherein said bidirectional conduction electronic switch comprises a triac having a gate electrode, and said threshold diode consists of a diac having one electrode connected to said gate electrode and another electrode connected to one plate of the capacitor of said threshold trigger circuit.

5. Electronic starter as set forth in claim 1, further comprising an impedance connected in parallel to said capacitor, said impedance being of such a value that, after the fluorescent lamp has been started, the voltage whereat said capacitor is charged at each half-wave of the supply a.c. voltage remains lower than the threshold voltage of said threshold diode in order to keep said electronic switch in the non-conduction state.

6. Electronic starter as set forth in claim 5, wherein said impedance is a resistor.

7. Electronic starter as set forth in claim 1, wherein said voltage divider comprises at least one resistor having a resistance value which is so selected to limit the time necessary for the current flowing through said electronic switch to build up.

8. Electronic starter as set forth in claim 1, further comprising another capacitor connected in parallel to said electronic switch, said other capacitor being adapted when said starter is in operation, to constitute together with a stabilizing coil connected in series with said fluorescent lamp, a series oscillating circuit capable of producing at each half-wave of said supply a.c. voltage and before starting the lamp, an oscillating overvoltage usable for controlling the conduction state of said electronic switch.

9. Two-pole electronic starter as set forth in claim 1, further comprising a second bidirectional-conduction electronic switch mounted in series with said first bidirectional-conduction electronic switch and having a control input, and a second threshold trigger circuit for delivering control pulses to the control input of said second electronic switch, said second threshold trigger circuit comprising a second threshold diode having one electrode connected to said control input of said second electronic switch, the capacitor of the first threshold trigger circuit having its other plate connected to the other electrode of said second threshold diode, the voltage divider having a second tap connected to the junction point between the capacitor and the second threshold diode, the potential shifting means being connected between the two taps of the voltage divider.

10. Two-pole electronic starter as set forth in claim 9, wherein said first and second bidirectional-conduction electronic switches consist of triacs mounted in series and in opposition, and said means 5 consists of a negative temperature coefficient resistor connected in parallel to said capacitor and arranged in heat transfer relationship with a heating resistor, said heating resistor being connected in series between said pair of triacs.

10 11. Two-pole electronic starter as set forth in claim 10, wherein said heating resistor and one of said pair of triacs are each connected to an auxiliary terminal of said starter, said auxiliary terminals being adapted to be connected to each other selectively through a removable short-circuit member or through relevant filaments, connected in series, of a pair of fluorescent lamps mounted in series across the pair of main terminals of said starter.

15 12. Two-pole electronic starter as set forth in claim 20 10, comprising a series circuit connected in parallel to said capacitor and consisting of a first resistor, of a parallel circuit and of a second resistor connected in series in this order, said parallel circuit comprising a third resistor in parallel to said negative temperature coefficient resistor, said series circuit having such an equivalent resistance value that when the fluorescent lamp has been started the voltage whereat said capacitor is charged at each half-wave of said supply a.c. voltage remains lower than the threshold voltage of said threshold diodes of the two threshold trigger circuits in order to keep both electronic switches in the non-conducting state.

25 13. Two-pole electronic starter as set forth in claim 35 11, which comprises a series circuit connected in parallel to said capacitor and consisting of a first resistor, of a parallel circuit and of a second resistor connected in series in this order, said parallel circuit comprising a third resistor in parallel to said negative temperature coefficient resistor, said series circuit having such an equivalent resistance value that after the fluorescent lamp has been started the voltage whereat said capacitor is charged at each half-wave of the supply a.c. voltage remains lower than the threshold voltage of the 40 45 threshold diodes of the two threshold trigger circuits in order to keep both electronic switches in the non-conducting state.
